UNITED STATES PATENT OFFICE.

GUSTAVE S. NEU, OF NEW YORK, N. Y.

THROTTLE-VALVE CONTROLLER.

SPECIFICATION forming part of Letters Patent No. 400,245, dated March 26, 1889.

Application filed May 11, 1888. Serial No. 273,624. (No model.)

To all whom it may concern:

Be it known that I, GUSTAVE S. NEU, of the city, county, and State of New York, have invented certain new and useful Improvements 5 in Throttle-Valve Controllers, of which the following is a specification.

My present invention relates to improvements in automatic power-controllers of the kind of which those shown and described in 10 two previous applications for patents—namely, No. 262,114, filed by me January 27, 1888, and allowed April 19, 1888, and No. 264,870, filed by me February 21, 1888—are examples. In each of these examples a main steam or 15 other power regulating valve is arranged to be operated in one direction by a weight or spring and in the opposite direction by an auxiliary motor connected with a steam, water, gas, or other fluid-power supply and itself 20 controlled by a self-acting power-supply valve in operative connection with the main-valve-operating devices, and catches are arranged to automatically engage and restrain both the main and secondary self-acting valves and to 25 be disengaged therefrom by electric or mechanical tripping devices, the arrangement being such that when the main-valve-restraining catch is tripped the main valve will be automatically operated by its weight or spring 30 in one direction, and when the secondary-valve-restraining catch is tripped the secondary valve will act automatically to start the main-valve-operating motor, and thus return the main valve to the restraint of its catch, 35 and at the end of the main valve's movement will be itself returned from its connection therewith to the restraint of its catch, and the motor thus stopped.

The main objects of my present improvements 40 are to provide simpler and more efficient mechanism for properly working the secondary valve from the main-valve-operating devices and the main valve from the fluid-power motor.

The invention consists of certain novel features of construction and combinations of parts, which will be hereinafter set forth in detail, and distinctly pointed out in the claims.

Reference is to be had to the accompanying 50 drawings, forming part of this specification, in which—

Figure 1 is a side, partly sectional, elevation of an automatic power-valve controller embodying my present improvements arranged to be operated by electricity. Fig. 2 55 is an enlarged cross-sectional elevation of the same on the line $x-x$, Fig. 1. Fig. 3 is an enlarged sectional plan view of a part of the same on the line $y-y$, Fig. 1. Fig. 4 is an enlarged sectional plan view of a part of the 60 same on the line $z-z$, Fig. 1.

In the device thus illustrated to show clearly the manner in which my present invention may be carried into effect the main fluid-power-regulating valve A , having the operating-arm A' , the forked lever D , for automatically engaging the valve-arm A' , the catch E , for automatically engaging the lever D and restraining the arm A' , the vibratory electric tripping device F , for disengaging the catch E and releasing the arm A' , the fluid-power motor M , for operating the valve A in opposition to its actuating weight or spring, the power-supply pipe L of the said motor, the vent-pipe M^3 , the motor-controlling valve L' , 75 its operating-lever L^3 , the forked lever N , for automatically engaging the arm of the lever L^3 , the catch N' , for automatically engaging the lever N and restraining the secondary valve L' , and the vibratory electric tripping device N^2 , for disengaging the catch N' and releasing the secondary valve, are all arranged on a supporting-frame, A^4 , to operate, in general, as shown and described in my previous application, No. 262,114, before referred to. In the 80 present instance, however, the main-valve arm A' is actuated by a weight, A^2 , which is adjustable on said arm, so that its effective force may be readily regulated as may be necessary. The piston-rod M^2 of the fluid-power motor M is also extended above the valve-arm A' , and the latter connected to the piston-rod M^2 by a pendulous link, A^3 , pivoted at its ends to the rod and valve-arm, respectively, so as to properly accommodate 85 the rotary movement of the valve-arm A' to the vertically-reciprocating movement of the piston-rod M^2 . Further, the motor-controlling valve L' is in this case a slide-valve of short travel, having its stem L^2 passed 90 loosely through the valve-operating lever L^3 , which is forked to embrace the cylinder of the 95

motor M and pivoted on opposite sides thereto and provided with stops l l' on opposite sides of said lever, so that when the arm of the lever L^3 is swung into engagement with the forked 5 lever N and catch N' , as shown in full lines in Fig. 1, the valve L' will be moved to cut off the steam or other fluid from the motor M, and when the arm of the lever L^3 is released by the action of its tripping device N^2 and is 10 swung downward to the position indicated in dotted lines in Fig. 1, the valve L' will be moved to open the admission and close the exhaust, as particularly set forth in my previous application, No. 262,114, before mentioned. 15

The mechanism here shown for automatically operating the secondary valve L' by the action of the main valve A, and embodying the principal feature of my present invention, 20 may be described in detail as follows: An inflexible rod, S, is passed loosely through the arm of the secondary-valve-operating lever L^3 , through a longitudinal slot, A^5 , formed in the main-valve arm A', and its upper end is 25 mounted to slide lengthwise in a guide, S' , fixed on the supporting-frame A⁴. A coiled spring, S^2 , is placed on the rod S between the main-valve arm A' and that of the secondary-valve-operating lever L^3 , and the lower end of 30 the spring S^2 is attached to a collar, S^3 , adapted to bear upon the lever L^3 and to be secured adjustably to the rod S by a set-screw, while the upper end of the spring is provided with a head, S^4 , adapted to be borne upon by the 35 under side of the main-valve arm A'. The adjustment and arrangement is such that when the main-valve arm A' is released by its tripping device and is carried downward by its weight A² to open or close the main valve, 40 as the case may be, it compresses the spring S^2 against the secondary-valve lever L^3 , which is, however, restrained by its catch N' , and thus, when the secondary-valve lever L^3 is released by the action of its tripping device N^2 , 45 the tension of the compressed spring S^2 will throw the lever L^3 downward and cause the valve L' to admit the steam or other fluid to the motor M and move the main-valve arm A³ in opposition to its weight A², all substantially in the manner described in my second 50 previous application, No. 264,870, above referred to.

On the operating-rod S, above the main-valve arm A', is arranged loosely a second coiled spring, T, the lower end of which rests upon a bearing, T', mounted to slide lengthwise on the upper side of the valve-arm A', over the slot A^5 therein, and having a tongue, T², fitted to slide in said slot A^5 without turning, so that the spring T will bear continually upon the arm A', while permitting the full play of the rod S in the slot A^5 of the arm A' as the same swings in its arc. On the rod S, above the spring T, is fixed an adjustable stop, 60 T³, against which the spring T is adapted to bear when the main-valve arm A' is swung upward. A catch, T⁴, is pivoted in a vertical

slot, A⁶, in the supporting-frame A⁴, and is borne upon by a spring, T⁵, so that its nose T⁶ will be normally projected outward in the path of the stop T³ and will engage and lock the same with the rod S and secondary-valve lever L³ against movement, so that as the main-valve arm A' is swung further upward, the spring T will be compressed between the same and the stop T³, against which latter its tension will thus be exerted. 70 75

An angular tripper, U, is pivoted to the supporting-frame A⁴ in such a manner that one arm, U', will project through the slot A⁶ 80 therein into the path of the bearing T', carried by the main-valve arm A', and the other arm, U², be adapted to bear upon the catch T⁴ while retained by a slot, U³, therein, the adjustment and arrangement being such that 85 just as the main-valve arm A' is engaged and restrained by the forked lever D and catch E the bearing T' thereon strikes, as a bearer, the arm U' of the tripper U, causing the arm U² of the latter to press the catch T⁴ rearward, so that its nose T⁶ will be disengaged 90 from the stop T³, which, being released, will be forced upward by the tension of the compressed spring T, carrying with it the rod S. The latter is provided with a stop, V, on its 95 lower end below the secondary-valve lever L³, which stop will bear upon the said valve-lever and return the same to the restraint of its forked lever N and catch N', thereby stopping the motor M and automatically setting 100 the whole apparatus in readiness to be operated again as before.

A guide, V', projecting outward and downward from the face of the frame A⁴, is arranged to receive and hold the main-valve 105 arm A' against lateral movement as it engages the angular tripper U. In the present instance the supporting-frame A⁴ is presumed to be of metal, and the ends of the main and secondary valve-operating arms A' and L³ and the various parts of the electric locking and releasing devices to be insulated from the frame and from each other, as in part indicated; but this insulation may be avoided by using a frame wholly or partly of insulating 110 material, as wood.

The electric circuit for operating the main-valve-working mechanism in this case is from the battery I through the wire I', the electro-magnetic vibrator G, the wire I², the spring 120 contact-piece K, the forked lever D when in engagement with its catch, the wire I³, the circuit-closer J, whether automatic or hand, and the wire I⁴ to the battery I again, so that when the circuit-closer J completes the circuit 125 the valve-arm A' will be released and fall, at the same time breaking the main circuit through the lever D, which is, by preference, made with a curved arm, D', to co-operate by sliding contact with the contact-piece K, 130 swinging out of engagement with said contact-piece K. The secondary-valve-operating circuit is from the battery-wire I' by the wire H, through the electro-magnetic vibrator N⁴,

the wire H' , the spring contact-piece O , the forked lever N , which, like the main forked lever D , has a curved contact-arm to co-operate by sliding contact with the spring contact-piece O , the wire H^2 , the self-opening circuit-closer R , which is arranged to be closed by the descending main-valve arm A' , as described in my first previous application, 262,114, but the lower contact-piece of which is yielding instead of rigid, as in my said previous application, the wire H^3 , the circuit-closer Q , whether automatic or hand, and the wire H^4 to the battery-wire I^3 , so that when the secondary circuit is completed by the circuit-closer Q , the secondary valve will operate first to start the motor M and return the main valve to the restraint of its catch, and then be automatically reset for operation, as also clearly described in my said previous application, No. 262,114.

This invention is also readily applicable to other operating devices whose action is similar to that of the main valve herein described.

I claim as new and desire to secure by Letters Patent—

1. In a device of the character described, the combination, with the cylinder, piston, ports, and slide-valve of a fluid-power motor, of a forked lever, L^3 , embracing the cylinder and pivoted on opposite sides thereto, the stem of the slide-valve working loosely through said lever and having stops l l' on opposite sides thereof, substantially as described.

2. The combination, with the arm A' of a self-acting valve, of a catch, E , for restraining the arm A' , a catch-tripping device, F , a fluid-power motor arranged to return said arm A' to the restraint of its catch, a valve for said motor having an operating-arm, a locking and releasing device for the motor-valve, a rod, S , working loosely through the main arm A' and

the motor-valve arm, a spring, S^2 , coiled on said rod between the two arms and adapted to be compressed by the arm A' , stops S^3 and V on the rod S on opposite sides of the motor-valve arm, and another stop, T^3 , connected to the rod and arranged to be moved by the arm A' , so as to reset the motor-valve, substantially as described. 45

3. The combination, with the arm A' of a self-acting valve, of a catch, E , arranged to automatically engage and restrain the arm A' , a catch-tripping device, F , a fluid-power motor arranged to operate the arm A' , a motor-controlling valve having an operating-arm, a self-locking and a releasing device for the motor-valve, a rod, S , connected to the motor-valve arm and working loosely through the main arm A' , a spring, S^2 , arranged to be compressed by the arm A' and to act on the motor-valve 60 arm, a stop, T^3 , connected to said rod above the arm A' , a spring arranged to be compressed by the arm A' and to act on the stop T^3 , a self-acting catch, T^4 , arranged to restrain the stop T^3 , and a tripper, U , for said catch arranged to be operated from the arm A' , substantially as described. 55

4. The supporting-frame A^4 , having a rigid forward and downward projecting guide, V' , to receive and retain the arm A' against lateral movement, as and for the purpose specified. 70

5. The swinging arm A' , provided with a sliding bearing, T' , through which the longitudinally-movable rod S is passed and on which rests the spring T , coiled on said rod, as and for the purpose specified. 75
